ABSTRACT OF THE DISCLOSURE

Manganese dioxide is produced by direct current electrolysis of aqueous sulfuric acid solution of manganese sulfate under specified conditions. Mn^{3+} ions are produced and are hydrolyzed with the formation of MnO_2 .

The present invention relates to a process for producing manganese dioxide by D.C. electrolysis of an aqueous sulfuric solution of manganese sulfate, wherein it comprises maintaining the anodic current density high, and also the concentration of sulfuric acid high, maintaining the temperature of electrolyte relatively high, so as to carry out hydrolysis of Mn^{3+} ion produced thereby, forming relatively coarse particles of MnO_2 and filtering it thereafter, heating the MnO_2 thus obtained in electrolyte, thus producing MnO_2 simply, inexpensively and efficiently, which has an excellent property as a depolarizer for dry cells, and at the same time, to utilize the filtrate produced after the filtration of MnO_2 for leaching manganese (as $MnSO_4$) from suitable raw material.

Heretofore, it has been well known to obtain manganese dioxide as the depolarizer for dry cells by D.C. electrolysis of a manganese sulfate solution, which comprises producing manganese dioxide, and applying thereon a washing and other after-treatments. The process of the production is as follows.

The electrolysis is carried out by a process, with conditions including: composition of electrolyte by 20–150 g./liter of $MnSO_4$ and 15–80 g./liter of H_2SO_4 ; temperature of electrolysis, above room temperature (for example: 30–100° C.); current density, 1–2 a./dm.²; depositing manganese dioxide in lump form on the anode (usually graphite or lead, sometimes titanium), then stripping it off from the anode, and to obtain the product by subjecting the material with trituration or other after-treatments. Another process is disclosed in Japanese patent application No. 1,696/1966 (published on Feb. 2, 1966), that is, the electrolysis is carried out at conditions: the composition of electrolyte, 10–30 g./liter of Mn^{2+} and 100–350 g./liter of free H_2SO_4 ; temperature, 10–30° C. (preferably 20° C. or below); current density, 35.5–59.2 a./dm.²; electrolytically oxidizing Mn^{2+} ions and hydrolyzing Mn^{3+} formed thereby, depositing granular MnO_2 , filtering and washing the product. A process has been proposed to use, by recirculating, the waste liquid from electrolysis for leaching of ores. However, since the former process is a batch type electrolysis and the current density is low, the productivity is low. In the

2

latter process, the exothermic phenomenon is conspicuous because of the high current load, and it becomes necessary to dissipate the heat, so that a large capacity cooling device is required in order to maintain the specified temperature of 10–30° C. (preferably below 20° C.) especially under a weather condition as in Japan, especially in summer. Thus, the amount of production per unit electrolytic cell becomes small as it is limited by the cooling capacity, so that it is not economical. Moreover, the product MnO_2 obtained by this process has a low purity and a large content of combined water, so that it has less favorable characteristics as a depolarizer for dry cells.

In the case where the manganese is leached as a sulfate from manganese-bearing containing ores, and when the raw material is in a form of oxides (Mn_3O_4 or MnO), it is necessary to add heat to effect solution to obtain a sufficient reaction rate.

Next, an oxidizing agent is added to the solution to remove impurities, especially metals (for example, Fe, etc.), contained in the raw material, to change Fe^{2+} into Fe^{3+} , then it is necessary to precipitate the metals of impurities as hydroxides, such as $Fe(OH)_3$, by filtration and separation in regulating the pH about 5. However, there were disadvantages that, when the solution is heated and regulated to have a pH of about 5, Mn^{3+} ions are hydrolyzed rapidly, producing a yellowish brown colloidal lump which is difficult to filter, and there is a loss of electrical energy required for oxidizing Mn^{2+} into Mn^{3+} ions, so that the current density is decreased.

The object of the present invention is to overcome and improve the above-mentioned disadvantages of conventional processes, and specifically, to deposit MnO_2 in the electrolyte by selecting the above described electrolytic

conditions. Namely, the invention is to provide a process for obtaining manganese dioxide for dry cells comprising, selecting operational conditions as: composition of electrolyte Mn^{2+} , 10–40 g./liter; free H_2SO_4 , 400–600 g./liter; temperature, 30–50° C.; anodic current density, 30–75 a./dm.²; anode being made of lead, lead alloy or lead oxide (for example, pure PbO_2 produced by electrodeposition), electrolyzing by D.C. while agitating solution to oxidize Mn^{2+} so that 5–15 g./liter of Mn^{3+} is contained in the electrolyte, carrying out a hydrolyzing reaction gradually according to the following formula:

so as to produce MnO_2 in the electrolyte, and to effect aftertreatments such as filtering, washing, drying, etc.

The further object of the present invention is to provide a process of producing efficiently manganese dioxide having an excellent discharge characteristic which comprises heating and agitating an electrolyte (containing Mn^{2+} and free H_2SO_4 having said concentration, 5–15 g./liter of Mn^{3+} produced by the electrolysis and MnO_2 produced by hydrolysis of Mn^{3+}) taken out of the electrolytic cell at a temperature of about 50–100° C. for 0.5–4 hrs., to obtain the product after filtering, washing, and drying the MnO_2 , or heating the electrolyte after filtering the produced MnO_2 from said electrolyte so as to convert Mn^{3+} contained in the solution almost up to MnO_2 , filtering it and adding MnO_2 which has been filtered first to this electrolyte which contains almost no Mn^{3+} (contain-

ing 0.1-0.7 g./liter of Mn^{3+}) by said heating and filtering, heating it while substantially returning MnO_2 formed by heating of Mn^{3+} to the electrolytic cell, subjecting the product after-treatments such as filtering, washing, drying, etc.

Here, temperature is determined at 30-50° C., because it requires a large capacity of cooling device in order to maintain a temperature less than 30° C., taking the temperature rise due to exothermic effect at the electrolysis into consideration. Accordingly the yield per electrolytic cell is restricted, and when the temperature is above 50° C., MnO_2 is liable to adhere on the surface of the anode which prevents the formation of Mn^{3+} ions, leading to a sudden decrease in current efficiency, and at the same time, brown-colored, minute particles are produced which are not appropriate for depolarizer for dry cells. The reason for selecting the anodic current density at 30-75 a./dm.² is that, with the density below 30 a./dm.², the productivity is low, and with the density more than 75 a./dm.², the current conducting members are overheated due to heavy current load and that minute particles are produced which are not adequate for depolarizer for dry cells.

With a free H_2SO_4 concentration below 400 g./liter, MnO_2 is deposited at the anode when the temperature reaches to 30° C., and which decreases in the current efficiency, thus it is not satisfactory.

When MnO_2 is heated in the electrolyte, the heating temperature is limited to 50-100° C. and the period is limited to 0.5-4 hours. This is because, with heating conditions with a temperature of below 50° C. and heating time below 0.5 hour, it is not possible to obtain an improvement in the purity of MnO_2 due to oxidation of lower oxides, nor an improvement in the characteristics of the product as a depolarizer. While with a heating condition of a temperature above 100° C. and the heating time more than 4 hours, the oxidation of the lower oxides does not proceed in proportion to the increase in temperature and time, so that the improvement in the characteristic of the product as a depolarizer cannot be expected.

The invention will now be described referring to the drawings, in which:

FIG. 1 is a flow diagram showing the process for production of manganese dioxide according to the process of the present invention;

FIG. 2 is a graph showing the relation between the heating temperature when MnO_2 is heated in the solution and the content of the combined water of MnO_2 ;

FIG. 3 is a graph showing the relation of the heating temperature and purity of MnO_2 ;

FIG. 4 is a graph showing the relation between the heating temperature and the content of lower oxide in MnO_2 ; and

FIG. 5 is a graph showing the relation between the heating time and the content of lower oxide in MnO_2 .

In the drawings the broken lines show the course of the oiliquid, slurry, etc.

raw material and MnO_2 , while the full lines show the

Referring to FIG. 1, the raw material and aqueous sulfuric solution of manganese sulfate to be used as a circulating acid are introduced in a leaching tank 1, to leach manganese component from the raw material. The manganese sulfate solution is supplied continuously to the electrolytic cell 2, and the D.C. electrolysis is carried out under agitation at a specified temperature.

Mn^{2+} is oxidized electrolytically to Mn^{3+} , and is hydrolyzed gradually, and MnO_2 is deposited in the electrolyte.

Slurry containing MnO_2 and Mn^{3+} ions is continuously discharged from the electrolytic cell 2, and the slurry is filtered by a filter to separate it into MnO_2 and the filtrate. The filtrate contains Mn^{3+} at high concentration together with H_2SO_4 and Mn^{2+} , the major part of which

are returned to the cell 2, and a portion thereof is heated in a heat-treatment tank 4, hydrolyzing Mn^{3+} to produce MnO_2 , filtering it in a filter 5, returning the produced MnO_2 to the electrolytic cell 2, which is used as seed, and the filtrate is passed to the heat-treatment tank 6. In some cases, the filtrate of the filter 3 is passed directly to the heat-treatment tank 6. MnO_2 obtained on the filter 3 is passed to the heat-treatment tank 6 and (the solution containing the filtrate from the filter 5, which contains H_2SO_4 , Mn^{2+} and whose Mn^{3+} concentration is decreased to about the equilibrium state by heating), is heated together with the filtrate from the filter 3 or after which filtering it by a filter 7 and separate it into MnO_2 and the filtrate.

MnO_2 is subjected to treatments such as neutralizing and washing 8, drying 9, etc., and is made into a product. The filtrate from 7 contains free sulfuric acid, Mn^{2+} , and low concentration Mn^{3+} , but it is returned to the leaching tank 1, and is used for leaching manganese from the raw material as a circulating acid.

Considered from the thermo-economical point of view, the heat required for heating 4 of the filtrate containing high concentration Mn^{3+} after separation 3 of MnO_2 discharged from the electrolytic cell 2 can be utilized for heating of MnO_2 in the following heat-treatment tank 6, and the heat required for heating the latter may be utilized effectively for leaching manganese portion from the raw material in the next leaching tank 1.

FIG. 2 is a graph showing a relation between the heating temperature and the content of combined water when MnO_2 is heated in electrolyte. When the content of the combined water is decreased by heating it at a temperature more than 100° C. in air for a long time, the performance is deteriorated as a depolarizer for dry cells, but when the content of the combined water is decreased by a heating in a solution as shown in FIG. 2, the depolarizing capacity is remarkably improved. FIG. 3 is a graph showing a relation between the heating temperature and the purity of MnO_2 , and it shows that the purity is increased as the heating temperature is increased. FIG. 4 is a graph showing a relation between the heating temperature and the content of lower oxide in MnO_2 , and FIG. 5 is a graph showing a relation between the heating time and the quantity of lower oxide in MnO_2 . They show that the content of the lower oxide is decreased as heating temperature is increased, as well as heating time is increased.

Some examples are given in the following:

EXAMPLE I

(A) Electrolysis

Electrolytic cell: 4 liters

Electrode:

Anode: Pure PbO_2 formed by electro-deposition

Cathode: Graphite

Distance between electrodes: 9 mm.

Composition of electrolyte:

Concentration of free sulfuric acid: 400 g./liter

Concentration of Mn^{2+} : 20 g./liter

Temperature: 37° C.

Current density: 45 a./dm.²

Mean bath voltage: 3.7 v.

Raw material: $MnSO_4$ solution containing 120 g./liter as Mn^{2+}

Quantity of raw material supplied: 200 ml./hr., continuous feeding

(B) Heating after electrolysis

Heating temperature: 95° C.

Heating time: 2 hours

Electrolyte used for heating contained 400 g./liter of H_2SO_4 , 20 g./liter of Mn^{2+} and 0.3 g./liter of Mn^{3+}

(C) Current efficiency and composition of MnO₂ produced

Current efficiency: 76.0%, 6 hours of electrolysis
Product:

Total Mn: 58.6%

MnO₂: 87.9%

Combined water: 7.0%

Pb: 0.009%

Crystal structure: γ -MnO₂

EXAMPLE II

(A) Electrolysis

Electrolytic cell, electrodes and the distance between electrodes are the same as in Example I.

Composition of electrolyte:

Concentration of free sulfuric acid: 500 g./liter

Concentration of Mn²⁺: 16 g./liter

Temperature: 45° C.

Current density: 60 a./dm.²

Mean bath voltage: 4.3 v.

Material: MnSO₄ solution containing 110 g./liter as Mn²⁺, obtained by leaching MnCO₃

Quantity of raw material supplied: 240 ml./hr. continuous feeding

(B) Heating after electrolysis

Heating temperature: 70° C.

Heating time: 3 hours

Electrolyte used for heating contained 500 g./liter of H₂SO₄, 16 g./liter of Mn²⁺ and 9.5 g./liter of Mn³⁺(C) Current efficiency and composition of MnO₂ produced

Current efficiency: 71.2%, 24 hrs. of electrolysis

Product:

Total Mn: 58.0%

MnO₂: 86.4%

Combined water: 9.8%

Crystal structure: γ -MnO₂ and a small amount of α -MnO₂

EXAMPLE III

(A) Electrolysis

Same cell as in Example I

Electrodes: Both anode and cathode are made of Pb

Distance between electrodes: 14 mm.

Composition of electrolyte, the same as in Example I

Temperature: 40° C.

Current density: 50 a./dm.²

Mean bath voltage: 3.9 v.

Material: MnSO₄ solution containing 100 g./liter as Mn²⁺, obtained by leaching MnO

Quantity of raw material supplied: 210 ml./hr., continuous feeding

(B) Heating after electrolysis

Heating temperature: 80° C.

Heating time: 1.5 hrs.

Electrolyte used for heating is the same as Example I

(C) Current efficiency and composition of MnO₂ produced

Current efficiency: 73.5%, 48 hrs. of electrolysis

Product:

Total Mn: 58.3%

MnO₂: 87.0%

Combined water: 7.5%

Crystal structure: γ -MnO₂ and a small quantity of α -MnO₂6
EXAMPLE IV

As the result of discharge performance test by 10 ohm continuous discharge based on JIS K 1467-1965, it was found that MnO₂ produced by the process according to the present invention, has "duration of closed-circuit at a voltage of more than 1.0 v." is increased about 15-20% as compared with the conventional products, and that it has remarkably excellent characteristics as depolarizer.

10 TABLE I.—DISCHARGE PERFORMANCE

		Minutes ¹
Commercial electrolytic MnO ₂		215
MnO ₂ produced by Japanese patent publication No. 1696/66		200

15 MnO₂ produced according to the process of the present invention

¹ Duration of closed-circuit at a voltage of more than 1.0 v.

20 As stated above, the effect or advantages of the present invention shown in the examples can be summarized as follows:

25 Since the temperature selected is high such as 30-50° C., no cooling device is needed for electrolyte, and it is easy to maintain the temperature constant. By heating MnO₂, produced by the electrolysis in the electrolyte having said composition, there were obtained a decrease in the quantity of combined water, increase in purity of MnO₂, decrease in lower oxide as shown in FIGS. 2-5;

30 "the duration of closed-circuit at a voltage of more than 1.0 v." is increased about 15-20% as compared with the conventional products, thus MnO₂ having remarkably excellent characteristics as a depolarizer was obtained. Moreover, by this heating, Mn³⁺ ions contained in the

35 solution are decomposed and deposited as MnO₂, and through which Mn³⁺ ions remaining in the solution can be lowered up to the equilibrium concentration, so that even when the solution is used for leaching of manganese from the raw material, the loss of electric energy

40 due to hydrolysis of Mn³⁺ ions, and therefore the decrease in current efficiency can be restricted to a minimum. Also, by adopting a series of procedures shown in FIG. 1, the heat required for heating the electrolyte, containing high concentration Mn³⁺ after separation of

45 MnO₂ discharged from electrolytic cell, can be utilized for heating of MnO₂ in the following electrolyte, and the heat required for heating MnO₂ in said electrolyte can be utilized effectively for leaching manganese from the raw material, respectively.

50 What is claimed is:

1. In an electrolytic process for producing manganese dioxide suitable for dry cells wherein direct current electrolysis is employed, the improvement which comprises conducting said electrolysis with an electrolyte containing a concentration of from 10 to 40 grams per liter of Mn²⁺ ion and from 400 to 600 grams per liter of free H₂SO₄, a temperature of from 330° C. to 50° C., and an anodic current density of from 30 to 75 a./dm.², to oxidize Mn²⁺ therein to Mn³⁺, and hydrolyzing the resulting

60 product containing Mn³⁺ to form MnO₂ in the electrolyte.

2. Process of claim 1, wherein said resulting product contains from 5 to 15 grams per liter of Mn³⁺.

3. Process of claim 1, wherein said electrolyte containing MnO₂ is heated at a temperature of from 50° C. to 100° C. for from 0.5 hour to 4 hours.

4. Process of claim 2, wherein said electrolyte containing MnO₂ is heated at a temperature of from 50° C. to 100° C. for from 0.5 hour to 1 hour.

5. Process of claim 1, wherein MnO₂ is separated from the electrolyte containing MnO₂ and is returned to said electrolysis.

6. Process of claim 1, wherein MnO₂ (1) is filtered from the electrolyte containing MnO₂; the resulting filtrate is heated and fine crystals of MnO₂ (2) are filtered therefrom and are returned to said electrolysis; and

MnO_2 (1) is heated at a temperature of from 50° C. to 100° C. for from 0.5 hour to 4 hours in the filtrate obtained by filtration of MnO_2 (2).
